UNITED STATES PATENT OFFICE.

WILLIAM G. ROOME, OF LOS ANGELES, CALIFORNIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING SYSTEM.

No. 920,654.

Specification of Letters Patent.

Patented May 4, 1909.

Application filed July 10, 1908. Serial No. 325,456.

To all whom it may concern:

Be it known that I, WILLIAM G. ROOME, formerly of Jersey City, New Jersey, but now of Los Angeles, in the county of Los Angeles 5 and Stat. of California, have invented certain new and useful Improvements in Railway Signaling Systems, of which the following is a specification.

The present invention relates to a system 10 of signaling, in which the movement of cars or trains is announced or recorded or both at a central office.

The system contemplates the use of an office or station at which the movement of cars 15 or trains is announced, which office or station would preferably be the despatcher's office. The despatcher may thus know the position of each and every train as it advances over the blocks or track sections. The despatcher 20 is also provided with a selecting device which includes a circuit extending along the blocks or track sections and which includes magnetic devices at each block or track section which he may separately control and operate. 25 These devices are arranged to secure the stoppage of the car or train. In the case of the application of the invention to the electric railways, the despatcher may cut off the operating current from the motors of a car or train in any block or section and thus compel 30 its stoppage, and at the same time the operating current may be cut off from the block or track section in the rear of this car or train so that a following car or train cannot run 35 into it. As it is sometimes necessary for steam railway trains to run over and use the same tracks as an electric car or train, provision is made for the setting of signals, and the system provides that all trains whether 40 electric or steam shall set protecting signals as they proceed. In addition, every precaution so far as electric cars is concerned, is provided, in case an electric car runs by a signal set at danger, in that its operating power is 45 shut off so as to compel its stoppage.

My invention also contemplates the use of a signal carried by a car or train as will hereinafter be more fully set forth.

I will describe a railway signal system embodying my invention and then point out the novel features thereof in claims.

In the accompanying drawings, Figure 1 50 illustrates diagrammatically a railway signaling system embodying my invention, and as 55 specifically applied to an electric railway.

Figs. 2 and 3 illustrate a method of connecting an announcing device magnetically to a signal or signal device which latter is operated by a train. Fig. 4 illustrates a method of electrically doing what is magnetically 60 done in Fig. 2. Figs. 5 and 6 are views of a selector. Figs. 7 and 8 illustrate connections made by a magnetic device controlled from the operating station.

Similar reference characters designate corresponding parts in all of the figures.

I will first describe the operation of the block system, and then the circuits and devices for automatically announcing or recording the position of the cars or trains, and 65 will explain circuits for enabling the despatcher to select a desired block or track section in which he may signal aboard the moving train or stop it if he desires, and will later explain the other protecting device and its 70 operation.

The blocks or sections are formed by dividing, as by insulation, the track or running rails of the railway. a , a^1 , a^2 designate three such sections. The section a includes a 75 track relay R connected to the rails at one of their ends by wires 22 and 23, and a battery B^3 which is connected to the rails at their other ends. The section a^1 includes relay R^1 wires 24 and 25, and battery B^4 . 80 Section a^2 includes relay R^2 , wires 28 and 29, and battery B^5 .

A signal or signal device is provided for each block or insulated track section. s^2 , s^3 and s^4 designate signals for the block sections a , a^1 and a^2 . Each signal comprises an operating mechanism and a device, usually a semaphore, which in different positions indicate to an engineer or trainman the condition of the block section in advance. The 85 operating mechanism of each signal generally comprises an electro-magnetic device which electro-magnetic device is included in a local circuit, comprising the armature of a track relay. The local circuit for the signal s^2 90 comprises a battery B , wire 12, armature of relay R , wire 13, electro-magnetic device of the operating mechanism of the signal s^2 and wire 15. The local circuit for the signal s^3 95 comprises battery B^1 , wire 16, armature of relay R^1 , wire 17, electro-magnetic device of the operating mechanism of the signal and wire 18. The local circuit for the signal s^4 100 comprises battery B^2 , wire 19, armature of the relay R^2 , wire 20 and electro-magnetic 105 device of the operating mechanism of the signal s^4 . The local circuit for the signal s^4 110 comprises battery B^3 , wire 21, armature of relay R^3 , wire 22, electro-magnetic device of the operating mechanism of the signal and wire 23.

device of the operating mechanism and wire 21. Ordinarily, with no train in a block section, the relay of that section will attract its armature to close the local circuit of the 5 operating mechanism to permit of the operating mechanism moving the signal device to an inclined or safety position. When a train is in a block section, the track battery of that section is short-circuited by the wheels and 10 axles of the train, thus shunting the track relay and permitting of the armature of the track relay to open the local circuit of the operating mechanism and allow the counter-weight of the signal device to move the signal 15 device to a horizontal or danger position of indication. It will be seen, therefore, that as a train proceeds along the block sections the signals of the block sections will be moved to a danger position when the train 20 enters a block section and will be moved to a safety position when the train leaves the block section. It is to this type of a signaling system that I preferably apply my invention. 25 In connection with the signaling system just described, or in connection with a similar railway system, I employ means which are put into operation either directly or indirectly by the passage of a train along the 30 block sections, which will send a signal to a central office or station which latter may conveniently be the despatcher's office. In the despatcher's office is located an indicating mechanism which may be audible or visual, 35 or both, for receiving the signals sent in by the aforesaid means.

30 designates a line wire which extends from a central station along the blocks or sections.

40 Y designates the means or device for giving a distinctive signal.

I do not wish to be confined to the use of this special kind of signal device shown for this purpose as many other signaling devices 45 of this kind would operate equally as well. The signaling devices as shown comprise a signal box which may be similar to the signaling boxes used in messenger service or similar to signaling boxes used in fire and 50 police telegraph systems. These signal boxes are adapted to open and close a circuit a number of times, the openings and closings being spaced differently in each box so that each box may give a distinctive signal. I show a box of this kind in Fig. 3 with 55 the cover removed. The wheel for signaling may be seen with the notches in it. In this particular case the notches would indicate that this box would give a signal of 1-3-2.

60 This signal would be received at the despatcher's office audibly on the bell G and printed on the tape of a register U in a similar manner to the system used in ordinary messenger service. The manner of connecting this box so as to be operated by the 65

train is shown in Figs. 2 and 3. As there shown, a rod b engages the handle of the signal box and the lower end of the said rod rests against or lies in close proximity to the balance arm e of the signal. Said rod is provided with a spring or yielding projection i, which is adapted to be engaged by a pin p on the balance arm e of the signal. It is intended, when the signal is set to safety position and the balance arm is raised to the upper dotted position that the pin p will engage the spring i and pass above it, and when the signal again goes to the danger position, that the balance arm will pull down the rod b to the middle dotted position where the pin will free itself from the spring i, permitting the spring in the signal box to lift the rod b and at the same time sending in its signal in the usual manner.

I do not wish to be confined to the use of a signal mechanism for operating the messenger or signal box, as it is obvious that the entire upper part of the signal including the signal blade, can be dispensed with. As for instance in Fig. 2 all the signal mechanism above the break in the drawing could be done away with and the signal operating motor and its mechanism used for moving the operating parts in the signal box Y alone. Nor do I wish to be confined to this manner of connecting the box Y with the signal mechanism as it may be operated by the motor gearing or any moving part of the mechanism. It being intended that the signal in going to danger position will operate the signal box Y. Nor do I wish to be confined to mechanically operating this box. I have therefore shown in Fig. 4 a manner of electrically operating the box Y. In this figure a track circuit a³ is shown energized by a battery B⁶ and controlling a track relay R³. Signal s⁵ is shown as having its signal motor M¹ connected in circuit with the battery B⁷ by the wires 31, 32 and 33. The relay R³ is adapted to open the wires 32 and 33 when there is a train in the section a³. When the relay R³ opens this circuit, the signal s⁵ goes to danger, as its motor M¹ is deprived of current. This motor M¹ is also rotated in the reverse direction and the relay R³ is adapted to place this motor on closed circuit through its back contact and the wires 32 and 34 and the magnet P¹ during the time that the signal s⁵ is moving to danger position. The armature of P¹ is mechanically connected in any convenient way. I here show a flexible connection to the handle of box Y. When the signal s goes to danger position the magnet P¹ will pull down the handle of box Y during the ascent of the signal blade and when the signal blade reaches danger position the motor M¹ will cease rotating and magnet P¹ will release the handle of box Y, and box Y will send in the signal in the usual manner.

The box Y is intended to be operated by the movement of signal s^3 ; and box Y' by the movement of signal s^4 . I have shown the signal blades dotted at the boxes to more clearly indicate the position of the signals s^3 and s^4 .

B^s designates a battery which is connected to the ground through the coil of magnet P on one side, and its other side is connected 10 to the wire 30 by means of the contact d and switch O. The circuit may be traced as passing through the boxes Y and Y' in succession, thence to other similar boxes, thence to ground. An arbitrary representation of 15 a telephone is shown at T and T' , and is shown as hanging on the ordinary telephone hook so that the lifting of the telephone off the hook will put it into the circuit of wire 30. The apparatus at the receiving station 20 consists in addition to the battery B^s and magnet P, of a double throw switch represented by the two switches O and O' connected by an insulated piece so that both are moved together. The contact d of switch O 25 is made a little longer than that of d^2 of switch O' . When the switches are moved together the contact at d^2 will be first broken. That is to say when the switches are moved to the left, and when they are moved to the 30 right the contact of d will first be restored. The object of this is to allow of throwing the switch O and cutting out of circuit the battery B^s without giving a false signal in the local circuit 35. When the engineer of a 35 train who has been stopped by a signal desires to communicate with the despatcher, he operates one of the signal boxes Y by hand at the signal where he is stopped. To distinguish this signal from one made automatically by the train, the engineer may 40 pull the box twice or the box may be constructed to be pulled farther than the distance it is moved mechanically and additional notches may be cut in the signaling 45 wheel for this purpose. Boxes of this description are in use for messenger service and many other purposes. Or the magnet P can be adjusted so that when the resistance of the telephone T is put in the circuit, it will 50 release its armature and close the local circuit 35 and the bell and register will respond. The despatcher may now throw over the switch O to the left and connect with contact d^2 putting a telephone T^s in circuit via wire 36.

The local circuit 35 comprises battery B^s , local bell G, register U, switch O ^{1} , wire 35, and the contacts of magnet P. U is an arbitrary representation of an ordinary 55 printing or embossing register and may include a roll of tape on which the signals may be preserved for record.

When a box such as Y is operated, the makes and breaks of the circuit made by 60 this box are repeated by the magnet P. This

magnet opens and closes the local circuit 35 a corresponding number of times and the signal is audibly announced by strokes of the bell G, and recorded on the tape of the register U. It will thus be seen that the 70 despatcher knows the position of each and every train, as it automatically signals its change of position every time it enters a new block or section. In order that the despatcher may control the passage of trains 75 or cars along the block sections from the central office or station, I provide means which will enable him to set to "danger" the signal of any desired block, and to the exclusion of any other signal. For this purpose 80 I preferably employ a selecting system.

40 designates a line wire which is shown as extending from the operating station or despatcher's office. This wire has in connection with it a selecting device at the despatcher's office or operating station arranged so that he may select any one of the blocks or sections of the system and by depressing a key may lock that section to the danger position, or he may signal directly to the 90 engineer in his cab, or he may test any signal apparatus or restore to the normal condition any track relay or magnet whose contacts have become stuck or fused together. In the present drawing I show a selecting apparatus with a step-by-step motion. I do not wish to be confined to this particular kind of apparatus as there are many kinds of selecting devices that would answer this purpose.

In Figs. 5 and 6 I show two views of a 100 selector I may use. I have designated this selector as I in the drawings and it may consist of a U-shaped frame or box n through opposite sides of which is passed an axle y to which is fastened a drum j around which 105 is wound a rope, to one end of which is fastened a weight w. Also fastened to the axle y is a ratchet wheel r. Also supported by the axle y, but loose on the axle, is a toothed metal wheel v to which is fastened a pawl g, 110 adapted to engage the teeth of the ratchet wheel r. On the front of the frame or box is painted a dial consisting of numerals. The axle y is in the center of this dial, and has a needle t fastened to it. This needle t is normally against a stop or pin p ^{1} . It may be remarked that the needle t being fastened to the axle y, to which is attached the drum and weight w, that the weight and rope on the drum is checked from unwinding by the 115 action of the needle t against the pin p ^{1} . An electric connection is made in any convenient way with the toothed metal wheel v. I show such a connection by the spring i ^{2} which is adapted to be always pressing against a 120 tooth or teeth of the wheel v. A second metal spring i ^{1} is adapted to make a contact with one or more of the teeth of the wheel v but only in passing. The arrangement of the pawl and ratchet is such that the wheel 125

will always stop in a position such as indicated by Fig. 5.

The operation of the apparatus may now be explained. The needle is shown as pointing to the numeral 1 and this denotes that by depressing the key N, the apparatus at station #1 will alone respond. The circuit may be traced from battery B¹⁰ which is shown as having its positive pole connected to the ground or earth and a few of its cells connected to the wire 39 passing through a switch O² and when key N is depressed to the wire 40, thence to station #1, to a rocking switch J. This switch J is composed of three arms and is preferably made of one piece of metal. The long arm is adapted to be in contact with one of the contacts d³ or d⁴. It is intended that the width of this arm of the switch will be greater than the space spanned so that one contact will be made before the other is broken and no break can occur in the circuit. One of the short arms of the switch J is normally in contact with the armature of a magnet P¹ and is intended to make an electrical contact through this armature. The other arm of the rocking switch J is adapted to engage the armature of a magnet P² when the switch has been shifted. I may here remark that the armature of magnet P¹ shifts the rocking switch so as to open a ground connection at station #1, and acts to connect the wire 40 to the wire 44 so as to cut out station #1, but this is not accomplished by the attraction of the armature of P¹ shifting the rocking switch J but depends on the armature of P¹ returning to its normal condition. For this purpose the wire 44 is opened by a back connection on the armature of P¹. These contacts d⁵ and d⁶ are insulated from the metal of the armature itself by the insulation h. The magnet P² is operated to restore the rocking switch J to the normal position. The circuit may be traced from wire 40 to switch J. Here the circuit has two paths, one through the long arm of the switch and contact d³ to wire 41, and the other through the arm of switch J, which is in contact with armature of magnet P¹ and through this armature and the wire 42 to the wire 41 and the coil of magnet P¹, thence by wire 43, passing through the coils of polarized relay R⁴, thence to ground. The few cells of battery B¹⁰ are not of great enough strength to operate the magnet P¹. This may be secured in a number of ways. By adjusting the spring of the armature of P¹ or by winding its magnets with heavy coarse wire so as to develop a small magnetic pull. The polarized relay R⁴ has, however, responded and crossed the rails of the track section a¹. This puts the signal s³ to danger in the same manner as would occur by the axle of a pair of wheels crossing this section. The engineer could take the telephone T off its hook at this sig-

nal and get instructions from the despatcher. The same is true of any signal. Or the despatcher if he wished to select the block or section in advance of station #1 would place the needle t of the selector I on the figure 2. 70 This would wind up the drum and weight w and the ratchet wheel r would move one tooth over the pawl g and on releasing the needle t, the weight w would move the needle back to the figure 1 and the action of the 75 ratchet r and pawl g would move the metal toothed wheel v so that one tooth would pass the spring i¹. This tooth in passing would connect momentarily the wire 40 with a heavy strong battery B¹¹ arranged to have, 80 as shown, its negative pole connected to the ground or arranged to be connected with an opposite polarity to the wire 40, to that of the battery B¹⁰. I may here explain that the polarized relays R⁴ and R⁵ are arranged 85 to respond when the battery B¹⁰ is to line and not to respond when the battery B¹¹ is to line. The battery B¹¹ is composed of a number of cells sufficient to energize the magnet P¹ so as to shift the rocking switch J. 90 Battery B¹¹ is connected by wire 37 and spring i² to the metal toothed wheel v and the tooth of this wheel in passing spring i¹ sends current momentarily over the wire 40 of sufficient strength to operate the armature 95 of P¹, and this armature now assumes the position shown in Fig. 7, shifting the rocking switch from the contact d³ to the contact d⁴. The circuit is, however, not broken, as the current still has a path through the armature 100 of P¹ and wire 42. The shifting of the rocking switch from contact d³ to contact d⁴ does not connect the wire 40 with the wire 44 as the wire 44 is held open by the back contacts d⁵ and d⁶ on the armature of P¹, but when the 105 break occurs at the selecting machine and the armature of P¹ is drawn back by its spring, the connection between this armature and the rocking switch is finally broken and the wire 44 is connected to the wire 40 by the 110 closing of the contacts d⁵ and d⁶. The position of the switch is now shown in Fig. 8. If now the key N be depressed the circuit of wire 40 is extended by the rocking switch J which is now in connection with the contact 115 d⁴ to the wire 44, which leads to station #2, and the rocking switch J¹ at this station. Here the circuit may be traced from wire 44 to the rocking switch J¹. Here the circuit has two paths, one to wire 45 by the long 120 arm of the switch and the other through the armature of P¹ and wire 46 to the wire 45, thence passing through the coils of P¹, wire 47 and the coils of polarized relay R⁵, thence to ground. This relay will now respond and cross the track circuit a². This shunts out the track relay R², setting the signal s⁴ to danger. The signal s⁴ in going to danger operates the signal box Y¹ and the despatcher now gets proof that he has operated this sig- 125

nal s^4 . I might state here that the despatcher in operating the signal s^3 would have operated the signal box Y in a similar manner.

5 The setting of the signal s^4 to danger also operates the controller F^1 , opening the wires 8 and 9, and disconnecting the conductor H of section a^1 from the feed wire 1. This would deprive the signal s of its current, and 10 it would go to danger, so that the despatcher could stop the car or engine E at this signal. The engineer could take the telephone T off its hook at this signal, and get instructions from the despatcher.

15 When the despatcher wishes to restore the selecting circuit to the normal condition, he releases the key N and depresses the key N^1 and the magnet P^2 will restore the rocking switch to the normal position. The circuit 20 may be traced from ground at key N^1 through battery B^{12} and over the wire 49 and through all the set of P^2 magnets in series, one of which is located at each station and the depressing of this key will cause all these 25 P^2 magnets to respond and all switches that have been shifted will all be restored together.

The circuit of wire 44 is continued beyond station #2 when the rocking switch J^1 is shifted, by wire 48 to other stations beyond 30 and at the end of the system may be grounded if desired for testing purposes.

It frequently happens in sleety weather 35 that the signals when operated at the normal safety position freeze to the safety position and means are provided for testing the signals in succession and keeping them moving so that they are not so liable to freeze and if they do freeze are detected. For this purpose I have provided the switch O^2 which throws 40 on the full strength of battery B^{19} when the switch is moved to the right.

When the key N is depressed the magnet P^1 and polarized relay R^4 at station #1 will 45 now both respond and on releasing the key the rocking switch at station #1 has connected the wire 40 to the wire 44 so now the second time that the key is depressed the magnet P^1 and polarized relay R^5 at station #2 will respond. Each time the magnet P^1 will 50 cut out its own station when the circuit is broken. It is intended that the despatcher will depress the key N and hold it down until the answer back signal from box Y shows that the signal s^3 has moved to the 55 danger position. He will then release key N and depress it again and hold it depressed until the answer back signal from the box Y^1 informs him that the signal s^4 has been moved. Any of the signals that have become frozen can be thus detected. There 60 are also many occasions where the controlling magnets, particularly the track relays, have their contacts stuck or fused together. This often happens during lightning storm. 65 It will be noted that a relay whose contacts

are so stuck together, is a dangerous thing, as it gives a safety signal when a train is occupying a block or section.

The signal boxes Y , Y^1 , each being arranged to give a distinctive signal and the 70 location of these signal boxes being known at the despatcher's office, it follows that the skipping of a signal in its regular order would denote that the signaling apparatus of that particular block or section was disarranged. 75 If now this had been caused by the sticking or fusing together of the contacts of the track relay and the particular section containing this relay having been located, it is only necessary to have another circuit in combination 80 with the selecting circuit to enable the despatcher to clear this relay. For this purpose additional contacts are arranged to be changed by the magnet P^1 . These contacts are operated by a piece of insulation h^1 , 85 placed on the armature of magnet P^1 and consist of a spring i^3 , which is normally in contact with a contact d^7 . When the armature of magnet P^1 is attracted, the insulation h^1 presses the spring i^3 away from the contact 90 d^7 . This position is shown in Fig. 7.

I have further combined with a track relay, such as relay R^2 of section a^2 , a magnet P^5 whose armature is adapted to separate the contact points of this relay. It is intended that the magnet P^5 shall be of sufficient strength to attract its armature and tear away the armature of relay R^2 from its contacts at all times. The circuit for this magnet may be indicated by the wire 50, and 100 includes battery B^{13} which is adapted to have one end grounded at key N^2 . It is intended that the wire 50 shall extend to a magnet similar to P^5 for controlling each track relay. Normally, the magnets such as 105 P^5 are shunted out of circuit by the wires 51 and 52. The signal box Y^1 in failing to respond to the passing of a train into this section would inform the despatcher that the signal apparatus of this section was 110 disarranged. I will here remark that the failure of Y^1 to respond is noted by the getting of the next regular signal in order, showing that the train passed over this block or section without setting the signal to danger position. 115 The despatcher will now operate the magnet P^1 at station #2 by means of the key N , and while holding the key N depressed the armature of magnet P^1 at station #2 will be attracted and the insulation h^1 will open the 120 wires 51 and 52 by pressing the spring i^3 away from the contact d^7 . While still holding key N depressed, the despatcher will now depress key N^2 , and the magnet P^5 will attract its armature and pull away the armature of the track relay R^2 . This will operate the signal s^4 and this signal s^4 will operate the signal box Y^1 and the answer back signal will be received at the despatcher's office. 125 It will thus be seen that by means of the 130

lecting device that the despatcher can test any and all of his signal circuits at any time and where the circuits are deranged by a fused track relay that he can restore them to 5 the normal condition. It will be noted that when the key N_1 is depressed, that should the polarized relay R^5 fail to respond, or should the relay R^5 respond and fail to cross the rails of section a^2 by bad connections or 10 otherwise, that by depressing the key N^2 the relay R^2 can be operated and the same result arrived at.

Referring again to Fig. 1, I have shown in connection with the railway signaling system 15 just described an electric railway system. In this system certain of the features are disclosed in my co-pending application, Serial No. 96,536, filed March 3rd, 1902.

In the present application the operating 20 current is adapted to be cut off from certain sections by the passage of a train and preferably upon the operation of the signals.

H designates a series of sectional feed conductors and H^1 a continuous conductor which 25 is connected with one terminal of a dynamo D or other source of electrical supply. If desired, one of the track or running rails of the insulated block section may be continuous in an electrical sense and serve instead of the 30 continuous conductor H^1 .

1 designates a line supply wire extending from the other terminal of the dynamo D , and 3, 4, 8, 9, branch wires leading therefrom to two of the sectional feed conductors H . 35 Included in the wires 3, 4, and 8, and 9, are circuit breakers or controllers F and F^1 . These circuit controllers may be operated in any desired manner by the passage of the train. Preferably they are operated from 40 the signals as described in the application hereinbefore mentioned. For example, the circuit breaker F is operated from the signal s^3 and the circuit breaker F^1 operated from the signal s^4 .

45 s , s^1 designate signals. The electro-magnetic controlling device of the signal s is connected to the sectional conductor H and the continuous conductor H^1 by the wires 10 and 11 and the electro-magnetic controlling device of the mechanism of signal s^1 is connected to another sectional conductor H by the wire 26 and with the continuous conductor H^1 by the wire 27. So long as the signal of any block section is in the inclined or safety 50 position of indication, the circuit breaker connected therewith will be operated to close the circuit between the line wire 1 and the sectional conductor H of the block section in the rear of that signal. Consequently the 55 signal s or a corresponding signal of that block will be held in an inclined or safety position. Should the circuit of the signal s or a similar signal be opened, it is an indication that the block section which it controls or the 60 signal next in advance is deprived of operat- 65

ing current. This signal is intended primarily to warn a motorman not to run into a block section which is deprived of operating power, and in effect, serves as a cautionary signal for the signal of the block next in 70 advance.

E designates an electric car, the wheels and axles A of which are shown as being in the block section a .

M designates the motor of the car and C a controller for the current to the motor.

L designates a signal lamp.

The circuit for the car may be traced from the dynamo D by wires 1 and 3 to the controller F , which may be of any desired construction which is here arbitrarily shown. Details of its construction and manner of connection may be found in the application hereinbefore referred to. The circuit for the motor continues from controller F by wire 4, 85 sectional conductor H , shoe K , wires 5, 6, and 7 passing through the motor M and any desired form of controller C , thence by shoe K^1 , conductor H^1 , and wire 2 to the dynamo D . The lamp L is connected across in multiple with the motor M and controller C . A steam locomotive may also be provided with a signal lamp and substantially the same connections above described may be employed. Of course, the motor M and its controller C may be omitted. The signal lamp 90

is normally on a closed circuit and automatically records the conditions of the block or sections in advance of the moving car or locomotive and in addition is arranged to be 100 controlled from the operating station or by the despatcher through the selecting system hereinbefore described. The despatcher knowing of the position of each and every car or train by means of the announcing and recording system is also enabled by means of the selecting system to separately operate the signal carried by any moving car or train without disturbing the signaling of any other car or train. The despatcher may thus give 105 any set of signals as flashes of the lamp in the car or train. A code of signals may thus be arranged. The despatcher may through the selecting system deprive the electric train from operating power at any desired point 110 and he can at that place either through the telephone system or through the lamp give any desired instructions.

What I claim as new and desire to secure by Letters Patent is:

1. In a railway signaling system, the combination of a number of cars or trains moving over successive sections of a block system, a sectional circuit extending along the block system, circuits extending along the blocks or sections containing electro-magnetic devices for separately controlling said sectional circuit, circuit controllers and means located at an operating station and co-acting with said circuit controller for separately operat- 125

ing a selected electro-magnetic device, nad a signal carried on each moving car or train for indicating the condition of the block in advance of that on which the car or train is 5 moving.

2. In a railway signaling system, the combination of a number of blocks or sections of a block system, a circuit extending along the blocks or sections including a device for 10 each block for automatically signaling the position of a car or train as it successively advances over the blocks or sections, means co-operating with and controlling the operation of said device, a combined operating 15 and receiving station where said signals are automatically announced or recorded, stoppage devices controlling the automatic signaling devices located adjacent to the cars or trains and under the control of the said combined 20 operating and receiving station and means located at the combined operating and receiving station for operating a selected stoppage device separately.

3. In a signaling system for electric rail- 25 ways, the combination of a series of conductors, controllers for connecting the conductors in circuit with a source of electric supply, means brought into and kept in action by the presence of a car or train on 30 any given block or section for cutting out of circuit the conductor in the rear, electric devices affected by such cutting out of circuit, and means located at a receiving station for automatically announcing or recording 35 the operation of the circuit controller.

4. In a railway signaling system, the combination of a series of conductors for carrying operating current, circuit controllers automatically operated upon the movement 40 of the signals due to the passage of a car or engine for connecting the conductors in circuit with a source of electric supply, a circuit extending along the blocks or sections including devices for automatically signaling 45 the operation of the circuit controllers, electric devices co-operating with the automatic devices, and a receiving station where said signals are automatically announced or recorded.

5. In a signaling system for electric rail- 50 ways, the combination of a series of conductors for carrying operating current, circuit controllers automatically operated by the cars or trains for connecting the conductors 55 in circuit with a source of electric supply, a circuit extending along the blocks or sections including electro-magnetic devices for separately controlling the operation of the circuit controllers, and means located at an operating 60 station for separately operating a selected electro-magnetic device.

6. In a signaling system for electric rail- 65 ways, the combination of a series of conductors in circuit with a source of electric supply, means located at a combined operating and

receiving station for selecting and operating a particular circuit controller so as to secure the operation of electric devices arranged along the blocks or sections and stoppage of the car or train at or near the desired block 70 or section, and means for automatically announcing or recording at the combined operating and receiving station the operation of the selected circuit controller.

7. In a signaling system for electric rail- 75 ways, the combination of a series of conductors, circuit controllers for connecting the conductors in circuit with a source of electric supply, and with devices arranged along the blocks or sections, means brought into and 80 kept in action by the presence of a car or engine in any given block or section for cutting out of circuit the preceding section, and means located at an operating station for selecting and operating a particular circuit 85 controller so as to secure the operation of device and stoppage of the car or engine at or near the desired section.

8. In a signaling system for electric rail- 90 ways, the combination of a series of conductors, circuit controllers for connecting the conductors in circuit with a source of electric supply, means brought into and kept in action by the presence of a car or engine on 95 any given section for cutting out of circuit the preceding section, and means located at a combined operating and receiving station for selecting and operating a particular circuit controller so as to secure the stoppage of the car or engine at or near the desired block 100 or section, and means for automatically announcing or recording at the combined operating and receiving station the operation of the selected circuit controller.

9. In a railway signaling system, a combination of a controlling circuit including a source of an electric supply and a circuit breaker having a movable part, a circuit controlled by the movable part of the circuit breaker, and a circuit including an electro- 105 magnetic device for separating the movable part from a contact of the controlled circuit when they have become stuck or fused together.

10. A combination of a controlling circuit 110 including a source of electric supply and a circuit breaker comprising a movable part, a controlled circuit including contacts with which the movable part co-acts, devices supplied by a control circuit for securing the 115 stoppage of cars and trains, and a circuit including an electro-magnetic device for separating the movable part of the circuit breaker from a contact when they have become stuck or fused together.

11. In a railway signaling system, a combination of a controlling circuit including a source of electric supply and a circuit breaker having a movable part, a controlled circuit including contacts with which the movable 120

- parts co-act, devices supplied by the controlled circuit for securing the stoppage of the cars or trains, a circuit including an electro-magnetic device for separating the contacts of the circuit controller when they have become stuck or fused together, and means located at a receiving station for automatically announcing or recording the failure of the movement of the circuit breaker.
12. A combination of a series of signal devices, means located at an operating and receiving station for automatically announcing or recording the failure of the operation of a deranged signal device and means under the control of an operator at the said station for operating the deranged signal device.
13. A combination of a series of circuit breakers located along the blocks or sections, means located at an operating and receiving station for automatically announcing or recording the failure of the operation of the circuit breaker, and means under the control of an operator at the said station for operating the last named circuit breaker.
14. The combination of a controlling circuit including a source of electric supply and a circuit breaker for a movable part, a controlled circuit including contacts controlled by the movable member of the circuit breaker, device operated by the control circuit for securing the stoppage of a car or train, a circuit including an electro-magnetic device for separating the movable part of the circuit breaker from a contact when they have become stuck or fused together, means located at an operating and receiving station for automatically announcing or recording the failure of the operation of the circuit breaker, and means under the control of an operator at the said station for operating the electro-magnetic device.
15. A signaling system for railways comprising a signal receiving station, a railroad track divided into sections, an electric device electrically associated with each said section of track and connected to the signal receiving station, and circuit controlling means whereby railroad cars in any section will send a distinctive signal to the signal receiving station.
16. A railway signaling system comprising a plurality of sections of railroad track, a signal receiving apparatus associated with said sections, and electric means including train
- wheels for sending distinctive indications to said signal receiving apparatus from said sections.
17. A railway signaling system comprising a plurality of sections of railroad track, a signal receiving apparatus associated with said sections, and electric means including closed circuit track portions controlled by train wheels for sending distinctive indications to said signal receiving apparatus from said track sections.
18. A railway signaling system comprising a plurality of sections of railroad track, signal receiving apparatus associated with said sections, track relays provided for said sections and operable through electric circuits including train wheels for controlling the indications of said signal receiving apparatus, and current supplying means for operating said signal receiving apparatus.
19. In railroading, means located at a common center, to detect the status of a series of blocks or subsections of the road of travel, in combination with means adapted to actuate the circuit adapted to operate the signal of the required section from said center or office.
20. In combination with the rails of travel divided into sections, each section provided with a circuit adapted to operate the signal, means located at a common center or office to detect the status of each of said sections, and means located at said center or office to actuate the signal circuit of one or the other of said sections.
21. In railroading, a center, signal circuits distributed along the road of travel and connected locally each to its respective section, a circuit for said center, said circuit running along the line of travel and in operative relation to the different signal circuits, and means stationed at the center, and operatively related to said circuit, to automatically and in order test and annunciate the status at said center of the different signal circuits.

In testimony whereof I have signed my name to this specification in the presence of the subscribed witnesses.

WM. G. ROOME.
